ABSTRACT OF THE DISCLOSURE

A mailbox stand having an upright support secured to horizontal telescoping tubular members. The telescoping connected to a mailbox with fasteners. The carrier has a longitudinal base carrying a sleeve telescoped over a stationary telescoping member. The forward end of the base is connected to the forward end of the movable telescoping member.

BACKGROUND OF INVENTION

It is conventional practice in rural and sparsely settled towns and villages to support R.F.D. mailboxes on upright poles or posts adjacent the roads or streets where mail carriers can conveniently place mail in the boxes from cars or trucks. In areas where there is an appreciable accumulation of snow, access to the mailbox is difficult if not impossible without changing the location of the mailbox relative to the snow drifts. This has been done by supporting the mailbox post in a movable stand so that the mailbox along with the post and stand is moved out into the roadway as the snow drifts accumulate. This presents a traffic hazard as well as interfering with the plowing of the snow. With the conventional stationary mailbox, the resident must shovel and remove a considerable amount of snow to provide convenient access for the mail carrier.

The object of the invention is to provide a sturdy low-cost mailbox stand which is readily expandable to move the position of the mailbox along with the build-up of the snow drifts and yet at the same time provide an area for the accumulation of snow that does not interfere with the snow plow. The mailbox is conveniently shifted relative to the snow banks so that the mail carrier does not have to fight the snow drifts to deliver the mail. The stand is designed to be spaced from the curb to permit the grading of the shoulders of the road during the temperate season of the year.

SUMMARY OF INVENTION

The invention relates to an extendible and contractible apparatus for movably mounting a mail box on a support. The apparatus comprises a first member connectable to the support and extended in a generally horizontal direction. Slidably mounted on the first member is a second member that forms with the first member an arm which may be varied in length by extending or contracting the second member relative to the first member. A releasable means connects the first member to the second member to fix the length of the arm. Secured to the second member is a carrier adapted to support a mailbox. The carrier has slide means which cooperates with the first member to mount the carrier on the first member whereby the carrier is supported by both the first member and the second member.

In the drawings:

FIGURE 1 is a side elevational view of the extendible mailbox support of the invention carrying a R.F.D. mailbox;

2

FIGURE 2 is an enlarged sectional view taken along the line 2—2 of the extendible and contractible arm and carrier of the support of FIGURE 1;

FIGURE 3 is a sectional view taken along the line 3—3 of FIGURE 2;

FIGURE 4 is an enlarged sectional view taken along the line 4—4 of FIGURE 2; and

FIGURE 5 is a view similar to FIGURE 2 showing a modified mailbox carrier.

Referring to the drawings, there is shown in FIGURE 1 the mailbox stand of this invention indicated generally at 10 supporting an R.F.D. mailbox 11 above the ground 12 adjacent curb 13 of a road 14. Stand 10 comprises an upright support 16 mounted in a solid base or anchor 17, as concrete, located in a hole above a gravel bed 18. The support 16 is a tubular pipe which extends through the concrete base 17 so that any water or moisture which may accumulate in the pipe will drain into the gravel bed 18. The support 16 is located adjacent the shoulder of the road 14 to provide a substantial space between the curb and the support so that road grading machinery and snow plows can function without the interference from the support.

Projected in a generally horizontal direction from the top of support 16 is an expandable and contractible arm indicated generally at 19. A connector 21, as an elbow, mounts the arm 19 on the top of support 16. The mailbox 11 is mounted on a carrier indicated generally at 22 supported on the arm 19. The arm 19 together with the carrier 21 is longitudinally movable to change the position of the mailbox 11 relative to the curb 13. This permits the mailbox to be moved out toward the road as the snow bank 23 accumulates on the curb and shoulder of the road. By keeping the mailbox 19 aligned with the edge of the snow bank, the mailbox is readily accessible to the mail carrier without the necessity of continuously moving large amounts of snow to provide access to the mailbox. As the snow bank recedes, the mailbox 11 can be moved back over the shoulder to its normal summer position. This is accomplished without disassembly of the arm in a minimum of time and effort.

Referring to FIGURES 2 and 3, arm 19 comprises a first generally horizontal tubular member 24. The inner end of member 24 is secured to the connector 21 so that the member projects in generally horizontal direction toward the road 14. Slidably positioned or telescoped in tubular member 24 is a second tubular member 26. The second member 26 is movable in a linear direction with respect to the first member 24 so as to either contract or expand the length of arm 19. The second member has a plurality of longitudinally spaced transverse holes 27 which are selectively aligned with a transverse hole 28 in the first member 24 to receive an eye bolt or pin 29. Pin 29 projects through the aligned holes to couple or connect the first member 24 with the second member 26. The length of the arm 19 is changed by merely removing the eye bolt 24 and aligning selected holes 27 and 28 according to the desired length of the arm. This changes the position of the mailbox 11 with respect to the side of the road 14.

Supported on arm 19 is the carrier 22 comprising an elongated linear back or base 31 secured at its outer end to a cap 32. The outer end of tubular member 26 is attached by a weld or similar means to the cap 32. Preferably cap 32 is a cup-shaped plug having a closed end. The bottom side of cap 32 has a drain hole 35 leading into tubular member 26. An upright slide means 33 in the form of a split sleeve is secured to the inner end of base 31 thereby positioning the base over the arm 19. As shown in FIGURE 4, slide means 33 surrounds the

first tubular member 24 with a loose slide fit and has a small slit or opening 34 on the bottom side opposite the back 31. The slit serves as a passageway for the drainage of moisture and water which may accumulate on the tubular member 24 which in cold weather would prevent the adjustment of the extendible arm 19 to change the position of mailbox 11.

Returning to FIGURES 2 and 3, a pair of transverse brackets 36 and 37 secured to the outer end of the back 31 form supporting members for the mailbox. The brackets 36 and 37 have upwardly projected ears 38 and 39 respectively at their opposite ends with holes to receive fastening members as nuts and bolts used to attach the mail box to the brackets.

The upper and inner portion of the arm 19 and carrier 22 is enclosed under an elongated shield 41 secured to the top of the rear portion of back 31. The shield as shown in FIGURE 1 extends from adjacent the back of mailbox 11 and over the slide means 33 thereby protecting telescoping parts of the arm from accumulating ice, sleet, slush, snow and the like.

Referring to FIGURE 5, there is shown a modified mailbox carrier indicated generally at 42 for supporting a pair of side-by-side mailboxes. The carrier 42 is mounted on an extendible and contractible arm indicated generally at 43 secured to an upright support or post similar to the support 16 shown in FIGURE 1. The arm 43 comprises a first generally horizontal tubular member 44 slidably accommodating a second tubular member 45. A transverse eye bolt or pin 46 is used to releasably secure the first tubular member 44 with the movable second tubular member 45. The carrier 42 has an elongated base or back 47 located linearly above the arm secured at its forward end to a rectangular frame 48. The forward cross member of frame 48 is connected to a cap 49 attached to the forward end of tubular member 45. The rear or inner end of base 47 is secured to a slide means or split sleeve 51 slidably located about the first tubular member 44. Sleeve 51 is similar to the sleeve 33 shown in FIGURE 4. The carrier 42 is used to support a pair of side-by-side mailboxes on the arm 43. The mailboxes are attached to pairs of transverse brackets 52, 53 and 54, 56, secured to the frame 48. Each end of each bracket has an upwardly projected ear 57 having a hole for receiving a fastening means used to attach the mailbox to the bracket.

In use, the arm 19 is attached to an upright support or post and extended toward the side of the road. In the temperate portion of the year, the arm is in a telescoped relationship as shown in full lines in FIGURE 1. The inner tubular member 26 is located within the outer tubular member 24. The pin 29 holds the members in assembled relationship. In this position, the shield 41 covers the back 31 and the slide means 33. With the carrier attached to the cap 32 and mounted on the first tubular member 44, mailbox 11 is rigidly supported. The carrier also permits the inner tubular member 26 to be telescoped up to the cap 32. This results in the maximum contraction of the arm 19 without sacrificing rigidity and stability of the carrier used to support the mailbox.

During the winter months of the year, snow accumulates on the shoulder and is plowed off the road into banks in the general vicinity of the mailbox support. To provide convenient access to the mailbox for the mail carrier, the arm 19 is extended by removing pin 29 and sliding the carrier and second tubular member 26 outwardly until the mailbox is positioned over the edge of the snow bank as shown in broken lines in FIGURE 1. The pin 29 is then reinserted through the aligned holes in the tubular members 24 and 26 to hold the mailbox in its selected extended position. The second tubular member 46 being provided with a plurality of longitudinally spaced transverse holes 27, as shown in FIGURE 3, can be adjusted in a number of extended positions so that the location of the mailbox 11 may be

varied in accordance with the position of the snow bank on the road. Thus, the mailbox is never extended beyond the point where it is a hazard to traffic on the road.

While there has been shown and described a mailbox stand as applied to preferred embodiments of the invention, it is to be understood that various omissions, changes and substitutions in parts and materials may be made by those skilled in the art without departing from the spirit of the invention. For example, the movable member may telescope over the fixed member of the arm, the cross section of the members may vary from square to circular or hexagonal and the members may be made of metal, plastic or wood. The upright support may be a post of metal, plastic or wood. Also, the shield can be eliminated or attached to the mailbox. The invention is defined in the following claims.

The embodiments of the invention in which an exclusive property or privilege is claimed are defined as follows.

- 20 1. An apparatus for movably mounting a mailbox on a support comprising: a first member connected to the support for extension in a generally horizontal direction, a second member mounted in sliding linear relation with the first member whereby the first member supports the second member in varying horizontal positions, means releasably connecting the first member with the second member, a mailbox carrier having a box support member secured to the second member, a slide means embracing the first member in linear sliding relationship and elongated means connecting the box support member and slide means to mount the carrier on the first member whereby the carrier is supported by the first member and second member and shield means mounted on the carrier to cover the top of the slide means.
- 25 2. The apparatus of claim 1 wherein the first member and the second member are telescoping tubular members.
- 30 3. The apparatus of claim 1 wherein the carrier is secured to the forward end of the second member and includes an elongated back located above the second member, said back secured to the top of the slide means.
- 35 4. The apparatus of claim 1 wherein said first member is a tubular member and said slide means is a sleeve means surrounding the first member with a slide fit.
- 40 5. The apparatus of claim 4 wherein said sleeve means has a slit along the bottom side thereof.
- 45 6. The apparatus of claim 1 wherein said carrier includes a bracket means securable to a mailbox.
- 50 7. The apparatus of claim 1 wherein said carrier includes a frame, and a plurality of bracket means secured to the frame for carrying a plurality of mailboxes.
- 55 8. The apparatus of claim 1 wherein the shield means is an elongated curved member covering the slide means and a portion of the first member.
- 60 9. The apparatus of claim 1 in combination with an upright support anchored in the ground and a connector means for attaching the first tubular member to the upper portion of the support.
10. The apparatus of claim 1 wherein said first member is a first pipe connected to the support and said second member is a pipe telescoped within the first pipe.
